UNITED STATES PATENT OFFICE

98,260

DESIGN FOR A COMBINED VENETIAN BLIND AND HOUSING THEREFOR

Peter H. Kuyper, Pella, Iowa, assignor to Rol-
screen Company, Pella, Iowa, a corporation of
Iowa

Application September 15, 1934, Serial No. 53,291

Term of patent 14 years

To all whom it may concern:

Be it known that I, Peter H. Kuyper, a citizen of the United States and a resident of Pella, in the county of Marion and State of Iowa, have invented a new, original, and ornamental Design for a Combined Venetian Blind and Housing Therefor, of which the following is a specification, reference being had to the accompanying drawing, forming part thereof.

Figure 1 is a perspective view of a combined Venetian blind and housing therefor in one position.

Figure 2 is a perspective view of a combined Venetian blind and housing therefor in another position; and

Figure 3 is an end view thereof.

The characteristic feature of my design resides in the upper portion of the Venetian-blind assembly, wherein the housing and top slat member are spaced apart substantially the same distance as are the slat members from one another, resulting in a surface at said upper portion of substantially the same uniformity as that of the slat-member area.

I claim:

The ornamental design for a combined Venetian blind and housing therefor substantially as shown and described.

PETER H. KUYPER.
